US00D596297S

(12) **United States Design Patent**
Huffman

(10) **Patent No.:** **US D596,297 S**
(45) **Date of Patent:** **** Jul. 14, 2009**

(54) **ARCH DENTAL ARTICULATOR BASE**2,827,899 A 3/1958 Altieri
2,842,845 A 7/1958 Carlson(76) Inventor: **Ronald E. Huffman**, P.O. Box 68440,
Oro Valley, AZ (US) 85704(**) Term: **14 Years**

(Continued)

(21) Appl. No.: **29/324,222**

FOREIGN PATENT DOCUMENTS

(22) Filed: **Sep. 9, 2008**

DE 3 436 094 A1 3/1985

Related U.S. Application Data(63) Continuation of application No. 29/256,994, filed on
Mar. 28, 2006, now Pat. No. Des. 576,734.

FIG. 1 is a top and front top perspective view of an arch dental
articulator base showing my new design;

FIG. 2 is a top and rear perspective view thereof;

FIG. 3 is a bottom and front perspective view thereof;

FIG. 4 is a bottom and rear perspective view thereof;

FIG. 5 is a front elevation view thereof;

FIG. 6 is a rear elevation view thereof;

FIG. 7 is a left side elevation thereof;

FIG. 8 is a right side elevation thereof;

FIG. 9 is a top plan view thereof; and,

FIG. 10 is a bottom plan view thereof.

The broken lines shown in the drawings are included for the
purpose of illustrating environmental structures and form no
part of the claimed design.**1 Claim, 5 Drawing Sheets**# US D596,297 S
